ARM PROPELLED SWING

Rolland Fletcher, Des Moines, Iowa

Application August 17, 1931. Serial No. 557,442

5 Claims. (Cl. 155—65)

This invention relates to improvements in swings and has for its principal object the providing of a swing that may be partly or wholly operated by the arms of the user as distinguished 5 from the usual swinging action produced entirely by the movement of the feet and body of the user.

A further object of my invention is to provide an arm actuated swing that reduces undesirable friction to a minimum.

10 A still further object of this invention is to provide an arm propelled swing that may be safely used without danger of accidental damage to the hand or hands of the user.

15 A still further object of my invention is to provide an arm actuated swing that requires only a minimum amount of movement of the arms to propel the swing.

20 A still further object of this invention is to provide an arm propelled swing that is economical in manufacture and durable in use.

25 These and other objects will be apparent to those skilled in the art.

My invention consists in the construction, arrangement and combination of the various parts 25 of the device, whereby the objects contemplated are attained as hereinafter more fully set forth, pointed out in my claims and illustrated in the accompanying drawing, in which:

30 Fig. 1 is a side view of my complete swing ready for use.

Fig. 2 is a rear end view of the complete invention secured to a supporting member.

Fig. 3 is a side view of a modified construction of the invention.

35 Fig. 4 is a side sectional view of one of the hand grip members and more fully illustrates its interior construction.

Fig. 5 is a top plan view of one of the hand grip members and illustrates the position of the 40 pulley wheel rotatably secured to the same.

The outdoor use of swings by young folks is very old and there is no question as to the fascination of its use. However one of its objections from a body and health building standpoint is 45 that the arms of the user do not experience sufficient exercise. I have overcome such objections by providing an arm propelled swing that may be installed either indoors or outdoors.

50 In the drawing I have used the numeral 10 to designate a supporting ceiling to which I secure my swing. The seat board of the device is designated by the numeral 11. Secured to each side portion of this seat 11 is a supporting rope or cable 12. These two supporting ropes extend upwardly in the usual manner and are secured in

any suitable way at their upper ends to the ceiling support 10. Slidably mounted on each of the supporting ropes 12 is a hand grip member generally designated by the numeral 13. These hand grip members may be made of any suitable material such as sheet metal stamped into desirable form.

In Fig. 4 I show such a product having a rope engaging member 14 in its upper portion and a rope engaging member 15 in its lower portion. By 65 providing two such rope engaging and bearing members as distinguished from a single bore completely through the handle member, the rope contacting surface is reduced to a minimum. Both of these rope engaging members have their 70 inner ends rounded in order to not unduly wear the rope extending through them. It will also be noted that these engaging and embracing portions 14 and 15 taper outwardly at their outer ends to more successfully guide the rope reciprocating in 75 them when the swing is in use. This is especially desirable if in the operation of the swing the handle members are pulled by the operator at an angle to the longitudinal axis of the supporting 80 ropes 12. The numeral 16 designates a hollow projection formed on the upper portion of each of the handles 13. This hollow projection extends laterally from the longitudinal axis of the handle member 13 and is open at its top. The numeral 85 17 designates a pulley wheel or roller rotatably mounted inside the portion 16. Directly above the pulley 17 is a bar 18. This bar 18 is a part 90 of the portion 16 and divides the open top of the member 16 into two open entrances 19 and 20. The numeral 21 designates an actuating rope or cable embracing the pulley 17 in each of the handle members 13. Each of these ropes have 95 their two lengths extending upwardly out of the portion 16 through the entrance openings 19, 20 respectively. The end of the rope 21 that extends through the openings 19 progresses to and is secured by suitable means to the ceiling support 10, as shown in Fig. 1. The points of securing these ends of the rope 21 to the ceiling support are directly in line but forward of the two points 100 where the supporting ropes 12 are secured to the ceiling support respectively.

The portion of each of the ropes that extends through the opening 20 continues upwardly and are eventually rigidly secured to the supporting 105 rope 12 adjacent to them, as shown in Fig. 2. The points of attaching these ends to the supporting ropes respectively are a substantial distance above any reciprocation of the handle members 13.

To use my novel swing it is merely necessary for 110

the one sitting in the swing to grasp the two hand grip members 13 and pull downwardly upon the same. This action will naturally shorten the distance between the points where the ropes 21 are secured to the supporting ceiling and the seat 11, thereby moving the seat 11 and its occupant forwardly. By permitting the hand grip members to slide upwardly the seat 11 will be permitted to swing to the rear. In other words, to use my swing the members 13 are reciprocated up and down by the use of the arms on the ropes 12. The amount of swinging action that results will be relative to the distance the members 13 are reciprocated up and down on the ropes 12. By the use of the pulley wheels 17 and construction shown in Fig. 1, not only will friction be reduced to a minimum, but the length of travel of the handle members 13 will be greatly reduced as distinguished from a construction wherein the ropes 21 would be directly secured to the handle members. This feature or features are very important for the reason that a great length of reciprocation of the handle members 13 would prevent those with short arms from swinging very high.

The invention is exceptionally safe to use, as the pulley wheels 17 and ropes 21 extending around the same are completely shrouded by the portion 16 which acts as a housing shield. Also, to prevent youngsters from reaching above the handles and receiving pinched fingers by the handle members and ropes 12 sliding therethrough, I have provided a peripheral flange 22 at the top of each of the handle grip members.

To provide a comparatively slow swing for small children, but one wherein great leverage is obtained, I recommend the construction shown in Fig. 3. In Fig. 3 the end of the ropes 21 are not secured to the supporting ropes, but extend around a bracketed pulley wheel 23 and then downwardly where they are secured directly to the handle grip members. These pulley wheels 23 are rigidly secured to the supporting ropes 12 at points near where the ropes 21 are normally secured to the supporting ropes 12.

From the foregoing it will be appreciated that I have provided a swing that will exercise all parts of the body including the arms and one that provides short reciprocation of its handle grip members.

Some changes may be made in the construction and arrangement of my improved arm propelled swing without departing from the real spirit and purpose of my invention, and it is my intention to cover by my claims any modified forms of structure or use of mechanical equivalents which may be reasonably included within their scope.

I claim:

1. In a device of the class described, a seat member, a flexible elongated member designed to have its upper end secured to a supporting member and its lower end secured to said seat member, a second flexible elongated member designed to have its upper end secured to the supporting member at a distance from said first-mentioned flexible elongated member and its lower end secured to said seat member, a hollow hand grip member slidably embracing said first-mentioned flexible elongated member, a roller secured to said hand grip member, a hollow hand grip member slidably embracing said second flexible elongated member, a roller secured to said last-mentioned hand grip member, an elongated flexible member engaging the roller on said first-mentioned hand grip member secured at one of its

ends to said first-mentioned flexible member at a point a substantial distance above said hand grip member and its other end designed to be secured to the supporting member at a point in advance of the point where said first-mentioned flexible elongated member is secured to the supporting member, and an elongated flexible member engaging the roller secured to said hand grip member on said second-mentioned flexible elongated member having one end secured to said second flexible elongated member at a point a substantial distance above said hand grip member thereon and its other end designed to be secured to the supporting member at a point in advance of the point where said second-mentioned flexible elongated member is secured to the supporting member.

2. In a device of the class described, a seat member, a flexible elongated member designed to have its upper end secured to a supporting member and its lower end secured to said seat member, a second flexible elongated member designed to have its upper end secured to the supporting member at a distance from said first mentioned flexible elongated member and its lower end secured to said seat member, a hand grip member slidably embracing said first mentioned flexible elongated member having a shield housing, a roller rotatably secured in said shield housing, a hand grip member slidably embracing said second flexible elongated member having a shield housing, a roller rotatably secured in said last mentioned shield housing, an elongated flexible member engaging the roller in said first mentioned shield housing secured at one of its ends to said first mentioned flexible member at a point a substantial distance above said hand grip member and its other end designed to be secured to the supporting member at a point in advance of the point where said first mentioned flexible elongated member is secured to the supporting member, and an elongated flexible member engaging the roller in said second mentioned shield housing having one end secured to said second flexible elongated member at a point a substantial distance above said hand grip member thereon and its other end designed to be secured to the supporting member at a point in advance of the point where the said second mentioned flexible elongated member is secured to the supporting member.

3. In a device of the class described, a seat member, a flexible elongated member designed to have its upper end secured to a supporting member and its lower end secured to said seat member, a second flexible elongated member designed to have its upper end secured to the supporting member at a distance from said first-mentioned flexible elongated member and its lower end secured to said seat member, a hand grip member slidably embracing said first mentioned flexible elongated member including a hand protective peripheral flange, a roller secured to said hand grip member, a hand grip member slidably embracing said second flexible member including a hand protective peripheral flange, a roller secured to said last mentioned hand grip member, an elongated flexible member engaging the roller on said first mentioned hand grip member secured at one of its ends to said first mentioned flexible member at a point a substantial distance above said hand grip member thereon and its other end designed to be secured to the supporting member at a point in advance of the point where said first mentioned

flexible elongated member is secured to the supporting member, and an elongated flexible member engaging the roller secured to said hand grip member on said second mentioned flexible elongated member having one end secured to said second flexible member at a point a substantial distance above said hand grip member thereon and its other end designed to be secured to the supporting member at a point in advance of the point where said second mentioned flexible elongated member is secured to the supporting member.

4. In a device of the class described, a seat member, a flexible elongated member designed to have its upper end secured to a supporting member and its lower end secured to said seat member, a second flexible elongated member designed to have its upper end secured to the supporting member at a distance from said first mentioned flexible elongated member and its lower end secured to said seat member, a hollow hand grip member including two bearing members having tapered openings and slidably embracing said first mentioned flexible elongated member, a roller secured to said hand grip member, a hollow hand grip member including two bearing members having tapered openings and slidably embracing said second mentioned flexible elongated member, a roller secured to said last mentioned hand grip member, an elongated flexible member engaging the roller on said first mentioned hand grip member secured at one of its ends to said first mentioned flexible member at a point a substantial distance above said hand grip member thereon and its other end designed to be secured to the supporting member at a point in advance of the point where said first mentioned flexible elongated member is secured to the supporting member, and an elongated flexible member engaging the roller secured to said

hand grip member on said second mentioned flexible elongated member having one end secured to said second flexible member at a point a substantial distance above said hand grip member thereon and its other end designed to be secured to the supporting member at a point in advance of the point where said second mentioned flexible elongated member is secured to the supporting member.

5. In a device of the class described, a seat member, a rope designed to have its upper end secured to a supporting member and its lower end secured to said seat member, a second rope designed to have its upper end secured to the supporting member at a distance from said first-mentioned rope and its lower end secured to said seat member, a hand grip member slidably embracing said first-mentioned rope, a rope-engaging member on said hand grip member, a hand grip member slidably embracing said second rope, a rope-engaging member on said last-mentioned hand grip member, a rope slidably engaging said rope-engaging member on said first-mentioned hand grip member secured at one of its ends to said first-mentioned rope at a point a substantial distance above said hand grip member thereon and its other end designed to be secured to the supporting member at a point in advance of the point where said first-mentioned rope is secured to the supporting member, and a rope slidably engaging the rope-engaging member on the said hand grip member on said second-mentioned rope having one end secured to said second rope at a point a substantial distance above said hand grip member thereon and its other end designed to be secured to the supporting member at a point in advance of the point where said second rope is secured to the supporting member.
